UNITED STATES PATENT OFFICE.

GEORGE E. ADAMS, OF NEW BRITAIN, CONNECTICUT.

DESIGN FOR A SUSPENDER-BACK CONNECTION.

SPECIFICATION forming part of Design No. 35,258, dated November 5, 1901.

Application filed May 1, 1901. Serial No. 58,391. Term of patent 14 years.

● *To all whom it may concern:*

Be it known that I, GEORGE E. ADAMS, of New Britain, in the county of Hartford and State of Connecticut, have invented and produced a new and original Design for a Suspender-Back Connection, of which the following is a specification, reference being had to the accompanying drawing, forming a part thereof.

10 The accompanying drawing is an elevation of a suspender-back connection embodying the present design.

As shown in the drawing, the leading or material features of the present design consist of the web A, formed into two upwardly

and outwardly extending loops a and two downwardly and inwardly extending loops a', with unions B extending upwardly from the loops a and a union C depending from the loops a'. Union C has two eyes c encircling 20 the loops a'.

What I claim is—

The design for a suspender-back connection substantially as herein shown and described.

GEORGE E. ADAMS.
